UNITED STATES PATENT OFFICE.

CHAUNCEY A. MICHAELS, OF NEW YORK (JAMAICA), NEW YORK.

DESIGN FOR A HOLDER FOR TOWELS AND OTHER ARTICLES.

59,765.

Specification for Design.

Patented Nov. 22, 1921.

Application filed June 21, 1921. Serial No. 479,385. Term of patent 7 years.

To all whom it may concern:

Be it known that I, CHAUNCEY A. MICHAELS, a citizen of the United States, and a resident of New York city, Jamaica, borough of Queens, in the county of Queens and State of New York, have invented a new, original, and ornamental Design for a Holder for Towels and other Articles.

Reference is to be had to the accompanying drawing in which the figure is a perspective view of a holder embodying my design.

I claim:

The ornamental design for a holder for towels and other articles as herein shown.

CHAUNCEY A. MICHAELS.
